(57) **CLAIM**

We claim the ornamental design for a base for fluorescent lamp, as shown and described.

DESCRIPTION

FIG. 1 is a top perspective view of a base for fluorescent lamp of the present invention;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof; and,

FIG. 8 is a perspective view of a second embodiment thereof shown in an environmental use.

The broken line showing of fluorescent lamp is included for the purpose of illustrating environment and forms no part of the claimed design.
